UNITED STATES PATENT OFFICE

LAIRD H. WALLACE, OF DENVER, COLORADO, ASSIGNOR TO THE E. & H. T. ANTHONY & COMPANY, OF NEW YORK, N. Y.

MAGAZINE-CAMERA.

SPECIFICATION forming part of Letters Patent No. 643,756, dated February 20, 1900.

Application filed September 1, 1899. Serial No. 729,172. (No model.)

To all whom it may concern:

Be it known that I, LAIRD H. WALLACE, a citizen of the United States, and a resident of the city of Denver, county of Arapahoe, State 5 of Colorado, have invented a new and Improved Magazine-Camera, of which the following is a specification, reference being had to the accompanying drawings, in which—

Figure 1 illustrates a plan view of the invention, the top of the camera or box being removed. Fig. 2 illustrates a vertical longitudinal section of the camera, taken through about its medial line, certain parts being shown in elevation and certain unimportant 10 parts omitted. Fig. 3 illustrates a perspective view of the magazine and certain of its coacting parts. Fig. 4 illustrates a perspective view of the exposure-chamber. Fig. 5 illustrates in elevation a detail of the magazine, the exposure-chamber, and the quadrant whereby they are operated. Fig. 6 illustrates 15 an elevation of the parts shown in Fig. 5, but in a different position. Fig. 7 illustrates a perspective view of a modified form of frame or support for the magazine and certain of the coacting parts. Fig. 8 illustrates an elevation of the magazine, the exposure-chamber, and certain of the coacting parts in a 20 slightly-modified construction. Fig. 9 is an elevation of the part shown in Fig. 8, but in a different position. Fig. 10 is a perspective view of the exterior of the camera, showing the lever and indicator whereby the devices 25 on the interior of the camera are operated.

30 A is the camera-box.

B is the lens, which is provided with a suitable shutter.

C is a handle whereby the apparatus as a whole may be carried.

35 D is the magazine. It is provided with spring-latches E E' E² E³, which are attached to its sides and project over one of the edges of the magazine, at what I call its "discharging" side or edge. The function of these 40 latches is to retain the plate-holders within the magazine until released and transferred. The magazine also has other spring-latches F F' F² F³, which are presented at the opposite side or edge of the magazine, and their 45 function is to take the plate-holders after exposure from the exposure-chamber and trans-

fer them to the rear side of the magazine in a manner which will be hereinafter explained.

G G G G are corner-blocks at the several corners of the magazine, against which the 55 compressor-plates H (see Fig. 2) rest when there are no plate-holders in the magazine, so that they will not drop away from it. The corners of the plate-holders themselves are beveled off slightly, so that they do not contact with these corner-blocks.

I I are springs which press the compressors apart and against the back sides of the plate-holders.

J J are pins set in one end of the magazine. 65 The magazine is supported upon lateral arms K, which are connected to a suitable part of the camera—as, for instance, to the back plate or end of the camera-box (marked A' in Fig. 2) or in any other way, as preferred. An alternative construction is shown in Fig. 7, 70 which will be hereinafter explained, and upon the ends of these arms, respectively, are pins L, which enter journals in the ends of the magazine. M M are two spring-latches connected with these arms K, which are engaged by the pins J to control the position of the magazine in a manner hereinafter to be explained.

N N are finger-like projections beyond the 80 edges of the magazine front and rear, which serve as guides for it in the manner hereinafter to be explained.

O is a cross-shaft journaled in any suitable way upon the bottom or in the sides of the 85 camera. One end of it projects through the side of the camera and is provided with a lever P, (see Fig. 10), whereby it is actuated, and within the camera and near the ends of the shaft O there are two quadrants keyed 90 to it, (marked Q,) at one side of which are upwardly-projecting studs R, provided with pins S. In the quadrants are two slots T T', and near the end of one of the quadrants is a click U, actuated by spring V and provided 95 with a hook W, which engages with a pin Y, which limits its movement. It is so arranged that when the quadrant is moved in the direction of the arrow (shown in Fig. 3) the click U engaging with the pins J J, respectively, will be depressed by such contact, 100 but as soon as it has passed the pins it will

be elevated again by the spring V, so as to engage with the pins upon the backward movement of the quadrant.

The plate-holders are shown at Z Z, (see Fig. 2,) most of them being shown at the receiving side of the magazine, which in this figure happens to be presented forwardly, but two of them, Z' Z', are shown at the delivery end of the magazine.

- 10 The exposure-chamber is shown in Fig. 4. It is composed of a box or frame *a*, having an opening *b* in its front, and is open entirely at the rear. *c c* are two spring-latches attached at the sides of the chamber, adapted to engage with the edges of the plate-holders by entering recesses *d d* in the magazine when it and the exposure-chamber are brought up close together, as will be hereinafter explained. The exposure-chamber is also provided with recesses *e e*, adapted to receive the beveled ends of the spring-latches *E, E', E², and E³*, and there is a plate or surface *fffff* at each of these openings which engages with the inclined ends of the latches, whereby they are lifted for the release of the plate-holders, and by the side of each of these recesses there is another recess *g*, within which, at the top and bottom, the guide-fingers *N* of the magazine enter, so that the parts are properly adjusted relative to each other, their edges being guided in such manner as to effect the proper transfer of the plates. On the vertical edges of the exposure-chamber there are other recesses *h h h h* and by the side of them smaller recesses *i i*, which receive, respectively, the side spring-latches *F F' F² F³* of the magazine and the side guide-fingers *N* thereof. At each side of the exposure-chamber, running vertically, there is a metallic plate *j*, having in it a slot *k*, within which the pins *S* of the quadrants work, so that as the quadrants make their quarter-revolutions they alternately project and retract the exposure-chamber.
- 45 *l l* (see Fig. 1) are latches whereby the rear of the camera-box is held in place. *m* is another one at the bottom of the camera, the latter being provided with a push-button *n*. (See Fig. 2.)
- 50 *o* is a smaller latch provided with push-buttons *p* at the upper side of the camera.
- 55 The operation is as follows: The parts are assembled as shown in Figs. 1 and 2, being in the first place in the position shown in Fig. 2—that is to say, the exposure-chamber is in the forward part of the camera in its position adapted to take pictures, and the magazine is presented with its receiving side toward the exposure-chamber, and the lever upon the 60 outside of the camera is in a horizontal position. The lever is now swung upwardly until a projection *p* upon its end engages with the last notch (marked *o*) on the indicator *q*. (See Fig. 10.) I prefer to make the lever *P* slightly spring-acting or elastic, so that the terminal finger *p* thereon shall snap into the notches in the gage positively, so that the in-

dition may be sure. Equivalent devices may be used for those just taken. As the quadrant tips over backwardly, due to the stated movement of the lever, the pins *s*, engaging with the slot *k* at the side of the exposure-chamber *a*, move the exposure-chamber backwardly toward the magazine, and as the quadrant moves the click *U* (which I usually have on one of the quadrants) engages with one of the pins *J* on the magazine and rotates it over forwardly toward the approaching exposure-chamber, and the pin *J*, with which the click engages during the movement of the quadrant, can enter the slot *t* therein, as may be desired, and as the next pin in turn moves downwardly it can enter the slot *t'* in the quadrant. As the magazine goes over one of the pins *J* comes in contact with the inclined or arc-like surface of the spring-latch *M*, which, as before stated, is attached to one or both of the arms *K*, upon which the magazine is supported, and presses this spring latch or latches, as the case may be, outwardly until the pin reaches its upper surface, whereupon the latch rebounds beneath the pin, so that backward turning of the magazine is prevented. The lever *P* is moved upwardly, as before stated, until the finger *p* on its end engages with the last notch of the indicator. When it has reached this position, the adjacent edges of the magazine and the exposure-chamber are brought snugly in contact with each other and the guiding-fingers *N N* upon the magazine have entered the recesses *i i* and *g g*, provided for them on the rear edge of the exposure-chamber, in such manner that these two receptacles are accurately registered with each other and brought into the desired relative positions. It will be observed that owing to the fact that the magazine has made a half-revolution by reason of the action of the quadrant upon it, as just described, the delivery side of the magazine is now in contact with the exposure-chamber, and that owing to the close contact secured, as above stated, between these parts the retaining-springs *E, E', E², and E³*, which normally hold the plate-holders within the magazine, have been moved by coming in contact with the plate *fffff* upon the exposure-chamber, so that the plates are freed within the chamber, and also that the spring-latches *c c* at each side of the exposure-chamber have 120 by their impingement against the edges of the foremost plate-holder been lifted and allowed to catch in behind those edges, since they have unobstructed movement within the notches *e e*, provided in the front edge of the magazine for this purpose, so that these spring-latches *c c* will upon the separation of the magazine and the exposure-chamber retain within the exposure-chamber and in proper focal position the said outside plate-holder. 125 To obtain proper focus, the lever *P* is now moved along the indicator to the proper distance, as shown thereon by figure or other indicia, and it will be observed that during the

forward movement of the exposure-chamber the magazine remains at rest, being held against rotation by one of the pins J, resting upon the upper side of the spring-latch M, 5 there being no movement of the magazine until the reverse or rearward movement of the exposure-chamber takes place. When it has been properly focused, the exposure is made in the usual way, and thereupon to remove 10 the exposed plate to the rear side of the magazine and substitute a fresh unexposed plate the lever is pressed farther forwardly to the end of its movement, so as to carry to completion the forward movement of the quadrant and bring the click in front of the pin J 15 on the magazine with which it is to coact. Upon reaching the extreme forward movement of the quadrant the lever is again brought rearward to a vertical position until 20 the catch p upon its extremity engages with the last notch (marked o) of the indicator, the same as before. In so doing the click U a second time engages with another one of the pins J and the magazine is rotated a half-turn, 25 the same as before, with the effect of now presenting the receiving side of the magazine to the exposure-chamber. The contact between 30 the two is made positive and certain in the same manner as above explained, with the differences, however, that when this—*i. e.*, the receiving side of the magazine—is brought in contact with the rear of the exposure-chamber the springs c c, which hold the exposed 35 plate within the exposure-chamber, are lifted by coming in contact with the edges of the magazine on which there are no notches d d, which were presented at the other side thereof, so that the retaining-latches c c are lifted, and the plate in the exposure-chamber is now 40 free to move, and simultaneously with the above operation the spring-latches F F' F² F³, which have free movement within the recesses h h h in the edge of the exposure-chamber, are lifted by the edges of the plate- 45 holder and catch over its forward surface, so that when the magazine and exposure-chamber again separate the plate will have been received within the rear side of the magazine and will be retained there and removed from 50 the exposure-chamber by these latches F F' F² F³. Now to again deposit an unexposed plate within the exposure-chamber the operation of the parts first described is repeated. In this manner the plates are in succession 55 transferred from the delivery side of the magazine into the exposure-chamber, there exposed, and then transferred back again into the receiving side of the magazine, and this is continued until all of the plates are exposed. 60

Although I have shown four spring-latches—*i. e.*, E E' E² E³—acting on the delivery side of the magazine and four other spring-latches F F' F² F³ acting upon the receiving side thereof, obviously a less number may be employed in both cases. Also it may not be necessary under all circumstances to have the

guiding or centering fingers N N, &c., with coacting notches in the exposure-chamber, and in Figs. 7, 8, and 9 I show a modified construction of certain of the parts, which in some respects I prefer to those illustrated in the other figures. They are as follows: Instead of employing the arms K, supported at the sides of the camera, above the bottom, and the spring-latches M upon them and having the shaft o journaled separately upon some suitable part of the camera-box it is advantageous under certain circumstances to employ the devices shown in Figs. 7, 8, and 9—that is to say, as a support for the magazine and coacting parts I make a frame of metal a', which may be attached by screws or otherwise to the bottom of the camera, and the trunnions L, upon which the magazine rotates, 85 I set in the inner faces of the two uprights of this frame, and at b' b' I make two journals within which the shaft O will operate, and in a projection c' from the frame a' I attach a spring d', having a hole e' near its end, and 90 projecting from the two edges of the magazine D, I provide two short pins f', which are adapted to enter the hole e' in the spring d', and upon the shaft o, taking the place of one of the segments, I arrange a mere bar or 95 crank-arm g', carrying the pin S, the same as before, and provided with a projection h', which is adapted to engage with the spring and depress it when it is desired to release the magazine for its rotation. This construction of the parts has the following advantages: First, inasmuch as the trunnions which support the magazine and the journals for the cross-shaft O are all within the same piece of metal their proper alinement and relationship to each other are permanently maintained; also, owing to the fact that the pins f' engage with the spring, depressing it and entering the hole e' therein at each half-revolution of the magazine, the latter is by this engagement prevented from rotating in either direction, whereas in the construction heretofore described and as illustrated, for instance, in Fig. 3 the latches M on the arms K hold the magazines against rearward rotation only. This is all that will be necessary in the majority of cases; but circumstances might arise in which it would be desirable to have the magazine held positively against rotation in either direction. 105

I do not limit myself to the details shown and described, since obviously they may be considerably departed from and yet the essentials of my invention be employed.

Having described my invention, I claim— 110

1. In a camera the combination of an exposure-chamber, a rotating magazine, means to move the said parts into contact with each other, means to rotate the magazine, means to transfer a plate from one side of the magazine into the exposure-chamber and other means to transfer a plate from the exposure-chamber into the reverse side of the magazine, for the purposes set forth. 115

2. In a camera the combination of a movable exposure-chamber, a rotating magazine, means to rotate the magazine and simultaneously bring the exposure-chamber into contact with it, means to transfer a plate from one side of the magazine into the exposure-chamber and other means to transfer a plate from the exposure-chamber into the reverse side of the magazine, for the purposes set forth. 45
3. In a camera the combination of a movable exposure-chamber, and a magazine, means to move the parts into contact with each other and means to transfer a plate from one to the other, for the purposes set forth. 50
4. In a camera the combination of an exposure-chamber and a magazine, means to laterally separate and bring together said parts, and means to transfer plates from one to the other actuated by the movement of the magazine and chamber toward and from each other for the purposes set forth. 55
5. In a camera, the combination of a movable exposure-chamber, a rotating magazine, means to cause the said parts to approach and recede from each other, means to prevent backward movement of the magazine, and means to transfer a plate from one to the other actuated by the approach of the parts toward each other for the purposes set forth. 60
6. In a camera, the combination of a rotating magazine, a movable exposure-chamber, a rack-shaft having a quadrant-like device which engages with the magazine for its rotation and with the exposure-chamber for its reciprocating movement and means to transfer a plate from one to the other for the purposes set forth. 65
7. In a camera, the combination of an exposure-chamber, a rotating magazine, adapted to receive plates at both of its sides, means to rotate the magazine and other means to reciprocate the exposure-chamber and devices upon the magazine and exposure-chamber actuated by the approach of the said parts toward each other, whereby a plate may be transferred from one side of the magazine into the exposure-chamber and from the exposure-chamber into the magazine at its reverse side, for the purposes set forth. 70
8. In a camera, a rotating magazine, and a movable exposure-chamber, a cross-shaft actuated by a lever upon the exterior of the camera provided with a focusing index device upon the cross-shaft, whereby upon the backward movement of the lever the magazine will be rotated and the exposure-chamber retracted, but upon the forward movement of the lever the magazine will be stationary and the exposure-chamber focused for the purposes set forth. 75
9. In a camera, the combination of a magazine and an exposure-chamber, devices to transfer a plate from the magazine to the chamber and other devices for returning the plate from the chamber to the magazine, and means for focusing the chamber which also actuate the magazine, for the purposes set forth. 80
10. In a camera, the combination of a magazine and movable exposure-chamber, and means to transfer a plate from one to the other, actuated by the approach of the parts toward each other, and means to focus the exposure-chamber upon the return movement thereof, for the purposes set forth. 85
11. In a camera, an exposure-chamber and a magazine, means to reciprocate the chamber toward and from the magazine, and means to transfer a plate from one to the other and means to focus the chamber, for the purposes set forth. 90
